UNITED STATES PATENT OFFICE.

TIMOTHY O'CONNELL, OF HOLYOKE, MASSACHUSETTS, ASSIGNOR TO THE WHITIN MACHINE WORKS, OF WHITINSVILLE, MASSACHUSETTS, A CORPORATION OF MASSACHUSETTS.

LAP-HEAD CONDENSER.

1,118,305.

Specification of Letters Patent. Patented Nov. 24, 1914.

Application filed June 7, 1913. Serial No. 772,224.

To all whom it may concern:

Be it known that I, TIMOTHY O'CONNELL, a citizen of the United States, and a resident of Holyoke, in the county of Hampden and 5 State of Massachusetts, have invented certain new and useful Improvements in Lap-Head Condensers, of which the following is a specification.

This invention relates to improvements in 10 mechanism for producing and winding laps into rolls and in which a relatively thin lap of textile fibers, such as cotton, or several of such laps superposed are to be wound into compactly layered rolls for subsequent operations, as for further drawing, combing and 15 the like.

The objects are, to provide means additional to the drawing or compressing rolls to smooth or iron the surface of the lap so 20 as to avoid the liability of adhesion between successive layers in the roll, so that the same can be unwound without damage either to the unwound layer or adjacent strata, further objects being to provide means whereby 25 the pressing, smoothing or ironing effect is readily adjustable to the thickness of the sliver and the degree of compression desired to impart to it, as well as to provide a construction that is applicable to existing ma- 30 chines without entailing expensive changes therein or the addition of extra parts. These and other objects are attained by the novel construction and arrangement of parts hereinafter fully described and shown in the 35 accompanying drawings, forming part of this specification, and in which:—

Figure 1 is a partial transverse sectional view of a ribbon lap machine indicating the application of the invention. Fig. 2 is a 40 partial plan view of the same. Fig. 3 is a perspective view, looking from the rear, of a condenser and smoothing device made in accordance with the invention, and Fig. 4 is an enlarged sectional fragmentary view 45 taken through the discharge orifice of the condenser.

The laps from the drawing rolls 10, of which there may be any desired number of sets, are received from the curved guide 50 plates 10^a upon the polished surface of the metal apron 11, where they are superposed as usual and along which the composite lap is advanced, as by rolls 12, and passed into a smoothing device such as shown in Fig. 3, 55 where the laps are preliminarily combined

and compressed, issuing from its narrow front opening to enter between the compression rolls 13, where the ribbon formed is delivered over the breast 14 to the winding drums 15 by which it is wound under pressure upon a spool or core 16.

The smoothing device is comprised of a body or main portion 20, formed with a longitudinally disposed central opening 21, adapted to receive the lap from the apron 11, 65 its internal side walls being rounded for the purpose of preventing irregular and ragged selvages and its entrance edge being sloped as indicated to provide easy access. On the upper side, near the ends of the main portion 20, are formed upstanding hinge lugs 23 registering with similar upstanding lugs 24 on the upper or cover portion 25 of the smoothing device. Pins 26 passing through these lugs 23 and 24, serve to pivotally connect the cover portion to the body. At the front or discharge portion, the wall of the cover and the opposing interior wall of the body are curved convexly or toward each 70 other, forming normally a narrow orifice 27, 75 extending close into the bite of the rolls 13, by which rolls the lap is drawn outwardly 80 and discharged on the breast.

The opening in the trumpet funnel or front part of the smoothing device, includ- 85 ing the orifice 27, is controlled by means of a lever 28 rigidly attached to the upper cover portion 25, which can be held resili- 90ently down under any desired pressure by the coiled spring 29 disposed between the 90 upper surface of the body 20 and the over- hanging portion 30 of the lever 28; this spring is tensionally adjustable by means of the screw 31 passing through the lever 30, where it is provided with a lock nut 32, 95 while its other end engages with the spring 29 and forms a thrust abutment therefor; a handle extension 33 of the lever 30 pro- 100 vides a convenient means for temporarily widely opening the orifice 27, which is de- sirable to do when piecing. The same handle provides means whereby the device in its entirety may be lifted and removed from the machine, for cleaning or any other purpose, it being understood that the 105 said device is adapted to rest on the end of the apron 11, remaining in place by its own gravity. It is hence readily adaptable to existing machines.

To prevent contact of the discharge end 110

with the condensing rolls 13, any suitable form of stop device may be provided, as, for instance, a lip or ridge formed on or attached to the end of the apron 11.

5 It will be understood that all the interior parts of the condenser are made smooth and highly polished so as to avoid impeding the passage of the ribbon therethrough; also that the rolls 13 may be substituted by drawing rolls for attenuating the lap, if desired.

10 From the foregoing it will be evident that this invention provides effective means for so smoothing or surface calendering the ribbon or lap that the tendency of the layers 15 in the roll to cling or adhere to each other is greatly reduced, when the lap roll formed therefrom is unwound; that therefore the quality of work is enhanced and loss in proportion caused by split laps, prevented.

20 Having described my invention and ascertained its use, what I claim as new and desire to secure by Letters Patent, is:—

25 1. The combination in a lap winding machine having an apron, of a sectional lap smoothing device placed thereon and means combined therewith whereby the comprised sections are yieldingly pressed together at the point of delivery.

30 2. The combination in a lap winding machine, of a lap smoothing device comprising two main sections providing a long and narrow opening between them and means for yieldingly constraining the sections toward each other to constrict such 35 opening.

35 3. In a lap winding machine, the combination with one or more pairs of compression rolls, of a lap smoothing device having a normally narrow discharge outlet, 40 and including a movable smoothing member and means for resiliently controlling said movable member.

4. In a lap winding machine, the combination with pairs of compression rolls, and an apron on which the laps therefrom 45 are superposed of a smoothing device adapted to receive the superposed laps and comprising a body portion, a movable element, means for resiliently pressing said movable element toward said body portion at the 50 point of lap delivery and means for adjusting the degree of pressure applied thereby to the lap.

5. In a lap winding machine, the combination with one or more pairs of compression rolls, of upper and lower members constituting a lap smoothing device, one being movable relatively to the other, pivotal connections between said members, means for holding said members together 60 under pressure, means for determinably adjusting the pressure means and means for temporarily overcoming said pressure means.

6. A smoothing device comprising a cast 65 body member formed with an inlet opening of fixed area extending through its rear portion, said member having a partially open top, a member hingedly connected to said body member, and so disposed within 70 the open top as to form a normally narrow, horizontally elongated, slot-like outlet conjunctively with said body member, means for maintaining a determinately constant pressure of said hinged member toward 75 said body member and normally operable means for operating the narrow outlet.

In testimony whereof, I have signed this specification in the presence of two witnesses.

TIMOTHY O'CONNELL.
